UNITED STATES PATENT OFFICE

OTIS W. NELSON, OF ATLANTIC, IOWA

SLATTED AUTOMOBILE BLIND

Application filed July 29, 1929. Serial No. 381,940.

The object of my invention is to provide a blind for automobile windows of slat construction, such blind being of simple, durable and comparatively inexpensive construction.

More particularly, it is my object to provide an automobile blind structure in which vertical guide means is connected between the upper and lower rails of a window frame of the automobile and a plurality of slats are slidably mounted on such guide means, the slats being provided with spacing mechanism and adapted to be moved to spaced position with such mechanism evenly spacing the slats from each other, whereby perfect visibility is secured when the driver looks through the blind and yet the rays of sun coming at an angle are prevented from entering the automobile.

A further object is to provide a slatted blind adapted to normally lie in collapsed position against the lower frame member of the window frame and capable of movement to extended position to serve as a blind in which position the driver may thrust his hand outwardly for signalling purposes below the lowermost slat of the blind element.

A further object is to provide a guide means for the blind, which may be readily adjusted to all heights of window openings.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a partial side view of an automobile showing one of my blind structures in connection therewith and in collapsed position.

Figure 2 is a similar view showing the blind in extended or shading position.

Figure 3 is a perspective view of the blind structure and the means for attaching the blind to the window frame of the automobile.

Figure 4 is an enlarged sectional view on the line 4—4 of Figure 1.

Figure 5 is an enlarged sectional view on the line 5—5 of Figure 2.

Figure 6 is a sectional view on the line 6—6 of Figure 5; and

Figure 7 is a sectional view somewhat similar to the upper portion of Figure 5, illustrating a modified form of connection for the guide means used in connection with the blind structure.

On the accompanying drawings, I have used the reference character A to indicate generally, an automobile. My blind structure is applied to one of the window frames thereof, having a bottom rail 10, top rail 12 and side rails 14. The window glass is indicated at 16.

The blind structure comprises a blind element B consisting of a plurality of slats 18, 20 and 22. 18 is the top slat and 20 the lower one, the intermediate slats bearing the reference numeral 22. Each of the slats is provided with a pair of openings 24. Spacing devices 26 consisting of tapes which may be secured to the edges of the slats 18, 20 or 22 by tacks or nails 28 are provided at each end of the blind element B.

Supporting hooks 30 are secured to the uppermost slat 18.

For the purpose of guide the blind element B relative to the window frame I provide a pair of coil springs 32 having their ends attached to cotter keys 34.

The cotter keys 34 are inserted through small openings 36 drilled in the lower and upper frame members 10 and 12 of the window frame.

The window frames of automobiles are usually provided with a movable molding member 38 secured in position by screws 40, which may be removed so that access can be had to the interior of the frame members 10 and 12 for bending the ends of the cotter keys 34 outwardly for anchoring them relative to the window frame members.

While the molding member 38 is removed, small blocks of wood 42 or metal, if found desirable, are inserted in the upper frame member 12 and screw eyes or screw hooks 44 are screwed through small openings 46 which have been drilled in the frame member 12 and into the blocks 42. The holes 46 are in align- 100

ment with the hooks 30 on the upper blind slat 18.

It will be understood, of course, that the blind element B is assembled on the springs 32 before they are attached to the window frame by the cotter keys 34. The springs 32 act as adjustable guide rods since they may be stretched to accommodate any height of window opening.

10 The blind element B normally rests on the window frame member 10 as shown in Figures 1 and 4 with the tapes 26 in folded or collapsed position, as clearly shown in Figure 4.

15 This position is assumed when the blind is not in use. When it is desired to use the blind the upper slat 18 is grasped by the driver and lifted toward the upper frame member 12. The hooks 30 are then adapted

20 to coact with the hooks or eyes 44, whereby the blind device is supported in extended and raised position, as shown in Figures 2 and 5.

Ordinarily, the blind structure is used when the sun is comparatively high and the rays 25 therefrom accordingly strike the blind in the manner illustrated by the arrows 48, (see Figure 5). The rays of the sun cannot get to the interior of the car and the blind acts as an effective shade even though the slats are 30 not adjustable as to inclination as in the ordinary type of Venetian blind.

It will be appreciated that providing for an adjustment would complicate the construction of the blind to a more or less prohibited 35 degree from a commercial standpoint.

I have found that a non-adjustable blind of this character effectively prevents the entrance of the sun's rays during the portion of the day when the blind is desirable and when 40 the sun is low, as in the evenings or mornings, it is not necessary to use the blind.

When the blind is in use, due to its slat construction, the driver can easily see through it without having to stoop.

45 A further advantage is that the blind is mounted completely within the car and on the inside of the glass 16 and does not project outwardly to be caught on branches or the like.

50 When the driver desires to signal, by thrusting his hand out of the window, he can readily do so by inserting it beneath the blind element B, which being light in weight, can be easily raised if there is not enough 55 room.

I propose to make my slats 18, 20 and 22 sufficiently long to accommodate the widest of windows and the ends thereof can be easily cut off to accommodate narrower windows.

60 In Figure 7, I have shown a modified form of construction in which instead of cotter keys 34 being provided for the ends of the springs 32, screws 50 are provided to extend through the openings 36 formed in the window frame members 10 and 12 and threaded

directly into the interior of the coil spring, which acts as a nut therefor.

The opening 36 is made large enough to allow the spring 32 to extend therethrough and engage the head of the screw 50. The slats 18, 20 and 22 may be made of wood or of sheet metal with reinforcing beads to strengthen them and other types of collapsible spacing mechanism may be provided instead of flexible fabric straps, as I have illustrated.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. For use with a window frame, a blind structure comprising vertically arranged coil spring guides carried by said frame, a slatted blind element comprising a series of slats each having openings for said springs whereby the blind element may be slidably supported on the springs, and means for attaching the top slat of said blind to the top member of said frame.

2. For use with a window frame, a blind structure comprising vertically arranged coil spring guides carried by said frame, a slatted blind element comprising a series of slats each having openings for said springs whereby the blind element may be slidably supported on the springs and collapsible spacing means for both the outer and inner edges of said slats.

Des Moines, Iowa, July 11, 1929.
